Fig. 3.

UNITED STATES PATENT OFFICE.

CARL FRANCIS SELPH, OF DE QUEEN, ARKANSAS, ASSIGNOR TO D. T. HULSE, OF DE QUEEN, ARKANSAS.

DRIER AND DEODORIZER.

Application filed August 22, 1923. Serial No. 658,839.

To all whom it may concern:

Be it known that I, CARL FRANCIS SELPH, a citizen of the United States, residing at De Queen, in the county of Sevier and State of Arkansas, have invented certain new and useful Improvements in Driers and Deodorizers; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to driers and deodorizers primarily intended for use in connection with cleaning and dyeing plants but it is also applicable for use as a laundry clothes drier and deodorizer.

One of the objects of the invention is to provide a drier and deodorizer adapted to contain clothes or garments which will be subjected to the action of the air passing through the drier and deodorizer so that moisture may be evaporated and the contents of the drier and deodorizer may be deodorized in an efficient and expeditious manner.

In carrying out my invention, I prefer to employ a closed casing in which the articles to be treated may be suspended on a rotatable carrier or cage through which air (preferably heated) may be passed, evaporating the moisture and carry off the odors. In the preferred form of my invention I contemplate the use of a heater for raising the temperature of atmospheric air and an air impeller of appropriate construction to cause the air to pass through the casing and come into intimate contact with the articles within the casing so that not only will the moisture be evaporated but the odors will be carried off. The novel construction of my invention will be apparent with reference to the following description in connection with the accompanying drawings, it being understood that I do not limit myself to the exact details of construction shown but reserve the right to make changes in form, proportion and minor details of construction without departing from the spirit of the invention.

Fig. 1 is a view partly in perspective and

partly in section of a drier and deodorizer constructed in accordance with my invention.

Fig. 2 is a cross sectional view through my invention and

Fig. 3 is a vertical longitudinal sectional view through the same.

In the embodiment of the invention selected for the purpose of illustration, I have shown a closed cylindrical casing consisting of the outside circular wall 1 and an insulating lining 2 and an inner wall 3. The vertical walls are connected to the bottom wall 4, the insulating lining 5 and inner wall or bottom 6. At the top there is an outer wall 7 and insulating lining 8 and an inner wall 9. The respective walls just described being so connected that a substantially cylindrical casing is provided with double walls between which is arranged an insulating lining which may consist of any appropriate material. At the upper portion of the casing is an inlet pipe 10 discharging air into the casing at one side of the axis of the casing to impinge against the clothes to cause rotation of the clothes carrying cage, the pipe having a damper or valve 11 adapted to be operated by a valve or damper stem 12 to vary the effective cross sectional area of the pipe. At the lower end of the casing is an outlet pipe 13 of appropriate dimensions.

Access may be had to the casing through an opening normally closed by a door 14 supported on the hinges 15. Within the casing is a vertically disposed rotating rod 16 supported at its lower end by the cross bar 17 and rotatably secured to the upper cross bar 18 by the guide pin 19. The rod 16 constitutes the axis of a rotatable cage to be described hereinafter. On the rod 16 is a speed governor consisting of the friction arms 20, cooperating with the projections 20' on the friction ring 21 to control the speed of the cage. The vertical spindle or rod 16 carries radial arms 22 on which are suitable garment supporting devices shown as hooks 23 by means of which articles to be dried and deodorized may be suspended from the arms. The outer ends of the arms are attached to a reticulated wall which may consist of a wire screen or suitable mesh and said screen may be provided with a door or

opening through which access may be had to the cage in order to introduce and remove the articles to be treated. In order to keep a circulation of air through the casing I may provide a suitable air impeller 25. The air impeller is shown as comprising an ordinary fan blower but obviously any suitable air impeller may be substituted therefor and in order to insure rapid evaporation of the moisture from the articles to be treated the air may first be passed through a suitable heater 26. I have not illustrated the heater nor the air impeller in detail because the particular construction 15 of either is unimportant as various types of heaters may be used and various types of air impellers may be employed, so I reserve the right to use any form of heater or any form of impeller which expediency may dictate.

20 When the parts are assembled the articles to be treated will be appropriately suspended in the cage and the casing will be closed. The damper 11 will be set to admit the proper volume of heated air into the 25 casing. As the air enters the casing under pressure, it will contact with the clothes and due to the fact that the cage is delicately poised within the casing the column of incoming air impinging on the clothes will 30 cause the cage to rotate so that the contents of the casing will progressively pass the inlet nozzle of the pipe 10, insuring a uniform application of heated air to the entire contents of the cage. Consequently all of the 35 articles in the cage will be subjected to a uniform application of incoming fresh air so that the entire contents will be dried at the same time, this being important for were it not for the fact that the cage rotated, the articles nearest the nozzle would 40 be subjected to an evaporated action while those more distant would still contain moisture. In actual practice I have found that not only does the device efficiently evaporate the moisture but it also deodorizes the 45 garments so when they are removed from the drier and deodorizer they will be sweet and clean. In the illustrated embodiment of my invention, I have shown the impeller 25 associated with the heater and discharging into the top of the casing. This is the preferred construction, but it should be recognized that the impeller might, with more or less success be located in the exhaust pipe 50.

55 13. Therefore my invention contemplates the use of the impeller either in the inlet pipe or in the exhaust pipe.

It will be apparent from the foregoing that with the construction shown the moisture in the articles in the cage is not only efficiently evaporated but since there is a forced circulation through the casing, all

odors must essentially be carried off through the pipe 13.

What I claim and desire to secure by Letters-Patent is:

1. In a drier and deodorizer, a casing having an air inlet and an air outlet, a rotatable clothes carrier in the casing and means for causing the air to be introduced under pressure into the casing at one side of the center to impinge against the clothes to cause the clothes carrier to rotate. 70
2. In a drier and deodorizer, a casing having an air inlet and an air outlet, a rotatable clothes carrier in the casing and means for causing the air to be introduced under pressure into the casing at one side of the center of the clothes carrier to impinge against the clothes to cause the clothes carrier to rotate, and a heater for heating the air prior to its passage into the casing. 80
3. In a drier and deodorizer, a casing, a vertical rotatable clothes carrier in the casing, an air inlet nozzle at the top of the casing at one side of the axis of the clothes carrier, an air outlet pipe at the bottom of the casing, and means for forcing air under pressure through the inlet nozzle to impinge against the clothes to rotate the carrier. 85
4. In a drier and deodorizer, a cylindrical casing, a vertical spindle in the casing, radial clothes carrying arms on the spindle, a reticulated wall carried by the arms and means for passing air horizontally into the casing, at one side of the axis at one side of the spindle, to impinge against the clothes to cause the spindle, the arms and the wall to rotate. 95
5. In a drier and deodorizer, a cylindrical casing, a spindle in the casing, radial arms on the spindle, clothes supporting means on the arms and a nozzle for directing air under pressure against the clothes at one side of the axis of the spindle to cause the spindle and arms to rotate to progress the clothes past the nozzle. 100
6. In a drier and deodorizer, a casing having an air inlet and an air outlet, a vertical rotatable clothes carrier in the casing, and means for governing the speed of rotation of the clothes carrier. 110
7. In a drier and deodorizer, a casing having an air inlet port and an air outlet port, a vertical rotatable clothes carrier in the casing, the air inlet port discharging into the casing at one side of the axis of the casing to impinge against the clothes to rotate the clothes carrier, and means for varying the effective port area of one of the ports. 115

In testimony whereof I affix my signature.

CARL FRANCIS SELPH.
